(57) CLAIM

The ornamental design for a trigger sprayer shroud, as shown and described.

DESCRIPTION

FIG. 1 is a front elevational view of a trigger sprayer shroud showing my new design, the rear being a mirror image;

FIG. 2 is a left side view thereof;

FIG. 3 is a top view thereof;

FIG. 4 is a right side view thereof; and,

FIG. 5 is a perspective view thereof.

The broken lines shown in FIGS. 1 to 5 are for illustrative purposes only and form no part of the claimed design.
